[57] CLAIM

The ornamental design for a combination cap and can holder, as shown and described.

DESCRIPTION

FIG. 1 is front perspective view of a combination cap

and can holder showing my new design, the broken line showing of the letter is for illustrative purposes only;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a front elevational view of a cap portion thereof;

FIG. 8 is a right side elevational view of the cap portion thereof, the left side being a mirror image thereof;

FIG. 9 is a top plan view of the cap portion thereof;

FIG. 10 is a front perspective view of a can holder shown separately from the cap for clarity of illustration;

FIG. 11 is a front elevational view of the can holder portion thereof;

FIG. 12 is a top plan view of the can holder portion thereof, the bottom being a mirror image thereof;

FIG. 13 is a left side elevational view of the can holder portion thereof;

FIG. 14 is a rear elevational view of the can holder portion thereof;

FIG. 15 is a right side elevational view of the can holder portion thereof;

FIG. 16 is a front elevational view of the can holder portion thereof; the broken lines indicating a can are shown for illustrative purposes only;

FIG. 17 is a back elevational view of the can holder portion thereof; the broken lines indicating a can are shown for illustrative purposes only;

FIG. 18 is a top plan view of the can holder portion thereof, the bottom being a mirror image thereof.
